(57) **CLAIM**

The ornamental design for a portion of a steering wheel for a game controller, as shown and described.

DESCRIPTION

FIG. 1 is a front perspective view of a portion of a steering wheel for a game controller showing our new design;

FIG. 2 is a front view thereof; and,

FIG. 3 is a top view thereof.

The broken line showing of the remainder of the steering wheel and the remainder of the game controller is for illustrative purposes only and forms no part of the claimed design.

The broken lines, which define the bounds of the claimed design, on the lateral spoke member, form no part thereof.
